STEEL WOOL FILAMENT

Original Filed Feb. 4, 1927

FIG. 1

FIG. 2

INVENTOR
William H. Robbins
BY Toulmin & Toulmin

ATTORNEY

UNITED STATES PATENT OFFICE

WILLIAM H. ROBBINS, OF SPRINGFIELD, OHIO, ASSIGNOR TO THE WILLIAMS COMPANY,
OF LONDON, OHIO, A CORPORATION OF OHIO

STEEL-WOOL FILAMENT

Original application filed February 4, 1927, Serial No. 166,001. Divided and this application filed November 28, 1928. Serial No. 322,568.

My invention relates to a mechanism, method and article for providing in a combination with steel wool a rope fabric or other form or shape associated with an absorbent material containing a soap, waterproofing material, rustproofing material, cleaning, polishing, shrinking or abrading compound.

5 This is a division of my application, Serial No. 166,001, filed February 4, 1927, which matured into Patent No. 1,698,512, dated January 8, 1929.

Referring to the drawings,

Fig. 1 is a diagrammatic view of the apparatus used for this purpose;

15 Fig. 2 is a perspective of a rope formed from the twisted strands of steel wool and textile material, the textile material having absorbed the liquid material, such as soap or the like.

20 Referring to the drawings in detail 1 is a tank in which is located a supply of liquid soap, waterproofing material or a rustproofing compound or any other cleaning or polishing material desired. In the tank is mounted a freely turning guide roller 3 underneath which the steel wool strand 4 and the textile strand 5 pass from the supply rollers 6 and 7 respectively. The combined strands after having been coated are wound

30 on a drum 8.

In Figure 2 there is shown a rope or filament formed from twisted strands of steel wool and textile materials. The textile strands 5 are impregnated with soap or some other cleansing material and twisted with strands 4 of steel wool, or some other abrasive material, to form a filament. The coating of the material 2 also appears on the steel wool strands but as the steel wool strand is not of absorbent material this will remain on the outside.

35 It will be understood that I desire to comprehend within my invention such modification as may be necessary to adapt it to varying conditions and uses.

40 Having thus fully described my invention, what I claim as new and desire to secure by Letters Patent, is:—

45 1. In an article of manufacture, one or more strands composed of steel wool and one

or more strands composed of textile material impregnated with a cleansing material, said strands being twisted to form a unitary rope structure.

55 2. In an article of manufacture, a plurality of strands of steel wool and textile material impregnated with a cleansing material and twisted about a central axis to form a rope.

60 3. In an article of manufacture, a plurality of strands of steel wool and a plurality of absorption strands impregnated with a cleansing material, said strands being twisted in a pattern to form a unitary structure whereby the absorptive material is evenly distributed with respect to the abrasive material.

65 In testimony whereof, I affix my signature.

WILLIAM H. ROBBINS.
